DANIEL S. COLBY AND ROBERT SCORER, OF TROY, NEW YORK.

Design No. 3,051, dated May 26, 1868.

DESIGN FOR PARLOR-STOVE PLATES.

The Schedule referred to in these Letters Patent and making part of the same.

TO ALL WHOM IT MAY CONCERN:

Be it known that we, DANIEL S. COLBY and ROBERT SCORER, of the city of Troy, in the county of Rensselaer, and State of New York, have invented or produced a new Design for Parlor-Stove Plates, of which the following is a full and exact description, reference being had to the accompanying drawings, and the letters of reference marked thereon, making a part of this specification.

Our said design consists of ornamental parts or figures arranged, in combination, in manner as follows, to wit:

In the annexed drawing—

Figure 1 represents an ornamental top plate and its urn of a parlor-stove.

This top plate is composed of an under part, C, and upper part A, hinged to the under part, and it has a series of surrounding ornamental mouldings, *a b c d*, and upon the hinged part A is placed an ornamental urn, B, of shell-and-scroll style of design, all as shown in said fig. 1.

Figure 2 represents the bottom plate of said stove, which plate is extended in front to form a hearth, D, and said plate is surrounded by the ornamental border-mouldings *g*, and a concentric inner ornamental border-moulding, *h*, all of detail design, as shown in said fig. 2.

Figure 3. F represents a leg of said stove, which is of ornamental design and configuration, the same as shown in said fig. 3.

What we claim as our invention or production, is—

The design for parlor-stove plates herein set forth, and shown in the annexed drawings.

DANL. S. COLBY,
ROBERT SCORER.
